UNITED STATES PATENT OFFICE.

AUGUST D. KUMPF, OF PHILADELPHIA, PENNSYLVANIA.

ACTUATING MECHANISM FOR WINDOWS, SASHES, SHUTTERS, OR THE LIKE.

Application filed November 17, 1920. Serial No. 424,714.

To all whom it may concern:

Be it known that I, AUGUST D. KUMPF, citizen of the United States, residing at Philadelphia, in the county of Philadelphia and State of Pennsylvania, have invented 5 certain new and useful Improvements in Actuating Mechanism for Windows, Sashes, Shutters, or the like, of which the following is a specification, reference being had to the accompanying drawings.

The present invention has for its purpose the provision of an improved actuating mechanism especially designed for use in connection with and operating windows, 15 sashes, shutters, or the like, such as are customarily pivotally or hingedly hung at their upper portions to the wall of a store, factory or other building.

Sashes or shutters for stores, factories or 20 other similar buildings are heavy and clumsy, therefore difficult to open and close, hence it is the aim to provide an actuating mechanism, wherein a plurality of toggle links are employed and are arranged so as 25 to force the shutter or sash outwardly, and to reinforce the sash in its outward position, in conjunction with means capable of being operated manually by a single operator, for moving the sash or shutter to an open or 30 closed position.

A further purpose is the provision of an 35 actuating mechanism, wherein means is included for cushioning the sash or shutter, when moving from an open to a closed position.

Still another purpose is the provision of 40 an actuator, wherein means is afforded for effecting an improved joint between certain of the toggle links and an endless actuator proper, whereby the movement of one side 45 of the endless actuator in the one direction and the movement of the other side in the opposite direction, will cause the toggle links to so operate, as to force the shutter or sash outwardly, and reinforce the same in its outward position.

A further purpose is the provision of an 50 actuator, wherein the endless actuator proper is provided with a fusible joint, 55 which, in case of fire, melts, thereby permitting the shutter to automatically close. The shutter is then free to be opened from the exterior by the firemen, in order to permit access to the interior of the building. Also in case of fire when the factory is not in 55 operation, the fusible joints are broken,

therefore the endless actuator proper is useless, and the shutter or sash may then be swung open, to permit of access to the fire 60 on the interior.

While the design and construction at present illustrated and set forth is deemed preferable, it is obvious that as a result of a reduction of the invention to a more practical 65 form for commercial purposes, the invention may be susceptible of changes, and the right to these changes is claimed, provided they are comprehended within the scope of what is claimed.

The invention comprises further features 70 and combination of parts, as will be hereinafter set forth, shown in the drawings and claimed.

In the drawings:

Figure 1 is a horizontal sectional view 75 through a portion of the wall of the building, preferably that of a factory, showing the improved actuating mechanism as applied to the sash or shutter.

Figure 2 is a view of a wall of a building 80 at right angles to the section shown in Figure 1, illustrating the improved actuator as applied and constructed in accordance with the invention.

Figure 3 is a horizontal sectional view 85 through the wall of the building and being similar to Figure 1, and showing the actuating mechanism in plan view, and as applied, with the shutter or sash extending outwardly.

Figure 4 is a sectional view on line 4-4 of Figure 3.

Figure 5 is an enlarged plan view of the 90 principal parts of said actuating mechanism, showing the same constructed in accordance with the invention.

Figure 6 is also a sectional view similar 100 to Figure 4, but showing the shutter or sash, as being pivotally mounted mid way its ends.

Figure 7 is a view in elevation of a slightly modified form of cushioning means for the endless actuator proper.

Figure 8 is a detail perspective view of 105 the connection between one of the toggle links and one of the rods of the actuator proper.

Figure 9 is a detail perspective view of one part of the connection shown in Figure 8.

Figure 10 is an enlarged detail view of 110 another form of actuator for the shutter, and showing the parts in elevation.

Figure 11 is a detail view of a portion of the endless actuator, showing the fusible joint in one side of the actuator proper.

Figure 12 is a detail sectional view of the 5 means connecting the endless actuator with the operating sprocket 27 and the sprocket chain 28.

Figure 13 is a sectional view on line 13—13 of Figure 12.

10 Figure 14 is a detail sectional view of the dash-pot 40.

Figure 15 is a detail view in elevation of 15 a portion of the actuator 16, the support 5, a portion of the closure 3, and the toggle link connections connecting the actuator, the support and the closure or shutter 3, showing intermediate positions of the toggle links.

Referring more especially to the drawings, 1 designates a wall of the factory or other building and 2 denotes the window opening, and 3 the sash or shutter for closing the opening. This sash or shutter or other closure is pivotally mounted at 4, either mid way its ends or at its upper end, so that it is the aim to open the sash or shutter at its lower end. In order to accomplish this operation, a series of toggle links are arranged at different locations and 30 connect the actuator proper and the shutter, so that by movement of the actuator proper, the shutter or sash may be swung outwardly at its lower end.

Arranged perpendicularly in the window opening 2 are I beams 5, and secured to the outer face of each beam as at 6 is a bar 7.

Suitable brackets 8 and 9 are carried by 40 the opposite side edges of the window opening, and mounted in bearings thereof are shafts 10 and 11. These shafts have sprockets 12 and 13 mounted thereon, which are engaged by the sprocket chains 14 and 15. Certain corresponding ends of these chains 45 are connected by a rod 16, and connected to one end of the chain 14 is a rod 17. A short cable 18 is connected to one end of the rod 17, and this cable 18 is in turn connected to the elongated screw or threaded stem 19 by means of a swivelled fusible joint 20, which is provided with a longitudinal groove 21, whose side walls are engaged by the guide 22, as shown in Figures 12 and 13, and which guide is supported by or forms 50 a part of a bracket 23, whereby said screw is thus splined upon said bracket and capable of longitudinal movement only thereon, and no rotary movement relatively thereto. The sprocket chain 15 which is connected to the rod 16 passes over the sprocket 13 and is connected at 24 to the screw or threaded stem 19. An internally threaded sleeve 25 is pinned or otherwise secured to the sleeve or extension 26 of the sprocket 55 27, which is actuated by the sprocket chain

28, it being apparent that the sprocket 27 and the internally threaded sleeve 25 rotate as a unit, said sleeve rotating in its bearing 29. The sprocket chain 28 can be actuated in any suitable manner as manually or otherwise, and it will be apparent that the rotation of the sprocket 27 and the sleeve 25 will cause the elongated screw or threaded stem 19 to travel longitudinally in the desired direction, thus imparting a pull or other movement in the desired direction to the connections 18, 19 and 14, thereby actuating the rods 16 and 17 in the desired directions.

Also mounted upon the shaft or pin 10 is a gear wheel 30, which meshes with segment gear 31, which is mounted upon a shaft 32, which is also carried by the bracket 8. An arm 33 is carried by the shaft 32, and suspended on the arm 33 by means of the rod or link 34 is a gravity member 35.

An eccentric 36 is mounted upon the shaft 10 to rotate therewith, and engaging said eccentric is an eccentric strap 37, which is pivotally connected at 38 to a plunger 39 of a conventional form of pneumatic cushion or dash pot 40. When the endless actuator member is operated, the chain 14 having been properly moved, the eccentric on the shaft 10 will cooperate with its eccentric ring, and owing to the dash pot or pneumatic cushion, the movement of the endless actuator proper will be cushioned. In other words the endless actuator proper will be prevented from operating suddenly, and through the medium of said brake or cushion 100 and the weight or gravity member 35, the shutter or sash will be prevented from dropping or closing with a bang, which would otherwise be the case, if it were not for the provision of the cushioning or brake means 105 and the gravity member.

Pivoted to the ends of the arms of the bar 7 as at 41 are links 42, which are in turn pivoted at 43 to the links 44. Each of the rods 16 and 17 of the endless actuator proper consists of end and intermediate sections 45 and 46, which are joined together by the couples 47, details of which are shown in Figures 8 and 9. These couples or joints comprise opposing members or blocks 48, which have correspondingly elongated grooves 49. These blocks or members 48 connect the straight line link motion with the window connecting bar. The two blocks or members 48 of each couple are duplicates in construction and may be fastened together in any suitable manner, preferably by means of bolts, such as indicated at 51. These bolts 51 also pass through the openings 49.

The links 44 are in turn pivotally connected on the bolts 51, and also mounted upon the bolts 51 pivotally are links 53, which are in turn pivoted at 54 to the bell crank links or levers 55. The bell crank 130

levers or links 55 are in turn pivoted at 56 to the links 57, which are in turn pivoted at 58 to the closure, sash or shutter 3. The arms 59 of the bell crank levers or links 55 are also pivoted at 60 to the links 61 and 64, the latter of which are in turn pivoted at 62 to the links 63, which are pivoted also upon the pins 41. The links 61 are also pivoted to the links 44 at 43. Links 65 are 10 pivoted also at 54, and at 41.

It will be seen that upon movement of the endless actuating means proper, for instance movement of the rods 16 and 17 in opposite directions as indicated by the arrows *a* and 15 *b* in Figure 2, that the various links connecting between the bar 7 and the rods 16 and 17 and the shutter or sash or closure 3, will assume positions shown in Figure 3 of the drawings, thereby moving the shutter or 20 sash to an open position as in Figure 3, and bracing the same. This operation will be accomplished by imparting motion to the sprocket 27 shown in Figure 12. When the shutter, sash or closure is moved to a closed 25 position, it may be cushioned upon the pneumatic cushioning means or dash pot 40, and prevented from closing with a noise.

In case of fire, the fusible swivelled connection between the cable 18 and the screw 30 or stem 19 may become melted, hence rendering the endless actuating means inoperative and in this case the shutter or closure will automatically close, and may be opened from the exterior by the firemen, in order to 35 gain access to the building.

In Figure 10 the various links are operable in upright positions, and are connected between the I beam and the endless actuator proper. In this figure the bar 7 is slightly 40 modified, in that its opposite arms are offset one above the other, and have depending right angle extension arms 66, and to which certain of the links or the series of links between the moving rods and the arms of the 45 bar 7 are connected. In this figure the rod 16 has one of its couples provided with a link 67, which in turn is connected to the flange 68 of the shutter or closure or sash 69, which is pivoted at 4 to the wall of the 50 building. It will be noted that when the rods 16 move in one direction and the rods 17 in the opposite direction, namely in this instance in directions toward each other, the links 67 will become angularly disposed and 55 the shutter or sash will be closed, and through the medium of the various link connections between the bar or plate 7 and the rod 16 will act to brace the rods 16 and 17 in their proper positions, when the sash or 60 closure or shutter is opened. One of the couples, for instance 70 of the rod 17 in Figure 10 has an arm 71, which cooperates with one of the couples of the rod 16, to limit the rods 16 and 17 in their movements in directions away from each other.

The invention having been set forth, what is claimed as being useful is:—

1. In a closure actuator of the kind set forth, the combination with a window opening having stationary supports disposed therein, of a closure for said opening, an endless actuator including rods operable in parallel planes in opposite directions, sets of toggle links arranged in lazytong-fashion connected to the rods of the actuator and 75 being in turn operatively connected to the stationary support, certain of said toggle links having arms provided with operative link connections with the closure, whereby upon movement of the rods in said directions, the closure may be moved outwardly, certain of said toggle links being engageable 80 with the stationary support, to limit the toggle links in their collapsed positions when the closure is closed, and means for preventing the closure from closing suddenly, and gravity means cooperating with the cushioning means, to prevent the closure from closing with a jar.

2. In a device for the purpose indicated, 90 the combination with a window opening, a closure therefor, an endless actuator, a stationary support, a plurality of toggle links arranged in lazytong-fashion and operatively connecting said stationary support and the 95 actuator, means operatively connecting certain of the toggle links and the closure for moving the closure to an open position when the toggle links are opened, means for operating said endless actuator, and means operatingly geared to the endless actuator for cushioning the same when operated.

3. In a device for the purpose indicated, the combination with a window opening having a stationary support disposed therein, of a closure for said opening, an endless actuator, moving means operatively connecting said stationary support and the actuator, means connecting the closure and the actuator for moving the closure to an open position when the first means is operated, means for operating said endless actuator, gravity means operatively geared to the endless actuator to assist in moving said actuator, and means operatively connected with the endless actuator and the operative geared connections between the gravity means and the endless actuator, for cushioning the actuator when operated.

4. In a device for the purpose indicated, 120 a window opening, a stationary support therein, a closure for said opening, an endless actuator including parts operable in parallel planes in opposite directions, each of said parts comprising a plurality of sections, coupling devices connecting said sections, means connecting said coupling devices and the stationary support and being operatively connected with the closure, whereby upon movement of the rods of the 125 130

actuator in said directions, the closure may move outwardly, means for operating said actuator, gravity means operatively connected with said actuator to assist in operating said actuator, and means operatively connected with said actuator for cushioning the same when operated.

5. In a window construction including a window opening, a closure for said opening, a stationary support disposed in said opening, an endless actuator including means for rendering it inoperative, a plurality of toggle links operatively connecting said sup-

port and the actuator for moving the same to an open position when the toggle links are open, and means including an eccentric and shaft operatively connected to the endless actuator for cushioning the same when operated, and a gravity actuated lever operatively connected with said shaft to insure a full operation of said cushioning means.

In testimony whereof I hereunto affix my signature.

AUGUST D. KUMPF.
